(57) **CLAIM**

The ornamental design for an abrasive head of deburring-machine, as shown and described.

DESCRIPTION

FIG. 1 is a front view of the abrasive head of deburring-machine, showing my new design;

FIG. 2 is a back view thereof;

FIG. 3 is a right side view thereof;

FIG. 4 is a left side view thereof;

FIG. 5 is a top view thereof;

FIG. 6 is a bottom view thereof; and,

FIG. 7 is a perspective view thereof.

The broken line in the figure drawings represents unclaimed portion of the design only, which forms no part of the claim.
